UNITED STATES PATENT OFFICE.

LUCIEN BIVA, OF WHITE PLAINS, NEW YORK, ASSIGNOR TO TITUS BLATTER & COMPANY, OF NEW YORK, N. Y., A CORPORATION OF NEW YORK.

DESIGN FOR TEXTILE FABRIC OR SIMILAR ARTICLE.

58,700.

Specification for Design.

Patented Aug. 30, 1921.

Application filed April 5, 1921. Serial No. 458,769. Term of patent 7 years.

To all whom it may concern:

Be it known that I, LUCIEN BIVA, a citizen of the Republic of France, residing at White Plains, in the county of Westchester and State of New York, have invented a new, original, and ornamental Design for Textile Fabrics or Similar Articles, of which the following is a specification, reference being had to the accompanying drawing, forming part thereof, which shows the design embodied in a piece of textile fabric.

It is to be understood, however, that my present ornamental design is applicable not alone to textile fabrics, but is intended, and is equally well suited for other articles of manufacture having surface ornamentation, such for example as carpets, rugs, wall paper, etc.

I claim:

The ornamental design for textile fabric or similar article substantially as shown.

In testimony whereof I affix my signature in presence of two witnesses.

LUCIEN BIVA.
